IMMERSION ANODE

George C. Cox, Charleston, W. Va.

Application April 22, 1946, Serial No. 663,854

10 Claims. (Cl. 204—286)

(Granted under the act of March 3, 1883, as
amended April 30, 1928; 370 O. G. 757)

1

The invention described herein may be manufactured and used by or for the Government for governmental purposes, without the payment of any royalty thereon.

This invention pertains to immersion anodes employed, for example, in the decomposition of sea water and similar electrolytes or in dissipating an electrical current into a body of substantially fresh water in situations in which polarization potentials are employed as an anti-corrosion aid. The invention is more especially directed to the provision of low resistance contacts and long-life connections between a non-metallic electrode (comprising one or more parts) and its lead-in conductor (cable or bus bar). Practical applications of the invention are to be found in the construction of anodes employed in the processes described in my United States Patent No. 2,200,469, dated May 14, 1940, or related processes.

In electrolyzing sea water or similar solutions containing soluble chlorides, as suggested in the aforesaid patent, and wherein a non-metallic electrode is employed, it has been found that the operative life of the connection between the lead-in cable or bus bar and the adjacent surface of the non-metallic electrode is quite short as compared for example with the life of the electrode as a whole, thus requiring a frequent replacement of the connections — an operation which is very expensive and troublesome in installations of large capacity. This deterioration usually manifests itself as a serious increase in the contact resistance between the terminal block of the "lead-in" conductor (either bus-bar or cable) and the adjacent non-metallic current carrying surfaces. Also, the deterioration of such an electrode system has frequently been found to be due to the partial or complete anodic solution of the "lead-in" bus bar or cable at or adjacent to its terminal block. Because of the increased voltage to force a given current through an electrode system having either one or both of these faults, the operating efficiency becomes lowered. Further continued operation with such faulty parts usually results in an inoperative electrode system.

While various kinds of non-metallic electrodes have heretofore been proposed and may be used effectively in the practice of the present invention, the invention is herein specifically described but without intended limitation, in its application to a carbon or graphite electrode.

A principal object of the present invention is to provide a novel method of and means for so uniting a non-metallic electrode to a lead-in

2

conductor as to provide a long life, low cost connection whose electrical resistance does not substantially increase throughout the life of the apparatus and such that those parts of the lead-in conductor adjacent to the electrode and which may be located near or beneath the surface of the electrolyte do not seriously deteriorate even during long periods of use. A further object is to provide a connection which is very strong mechanically and whose parts do not loosen or separate as the result of electrolytic or other action during use and which affords an electrical path of ample transverse area to insure low resistance at the junction surfaces even though the apparatus be submerged in saline water for long periods. Broadly stated, the invention provides a highly efficient and durable electrical union between a non-metallic anodic-insoluble electrode and a metallic conductor by means of a body of metal having a depressed anodic surface solubility.

Other and further objects and advantages of the invention will be pointed out in the following more detailed description and by reference to the accompanying drawings wherein

Fig. 1 is a fragmentary more or less diagrammatic, diametrical section through an anode united to a lead-in cable by the improved connections of the present invention;

Fig. 2 is a section on the line 2—2 of Fig. 1;

Fig. 3 is a fragmentary side elevation of a standard carbon or graphite electrode of cylindrical shape, the end portions of this electrode being shown in diametrical section;

Fig. 4 is a diametrical section of a connecting nipple in accordance with one embodiment of the present invention;

Fig. 5 is a diametrical section showing the nipple of Fig. 4 inverted and illustrating one of the preliminary steps in anchoring the lead-in cable to the nipple;

Fig. 6 is a diametrical section similar to Fig. 4, but illustrating a modified form of nipple;

Figs. 7, 8 and 9 are similar views illustrating further modifications;

Fig. 10 is a similar section illustrating a nipple of tapered form; and

Fig. 11 is a fragmentary, diametrical section through a compound anode comprising a plurality of electrodes.

Although a non-metallic anode for the electrolysis of saline water may be made as a single piece of material, it is desirable and very economical to form the anode from standard commercial parts. For example, the threaded-nipple

type of graphite electrode which is manufactured in an assortment of standard sizes may be easily and cheaply modified for the construction of the anode herein illustrated. Such a standard electrode is shown in Fig. 3. This electrode is a cylindrical rod 1 of amorphous carbon or graphite having internally screw-threaded axial bores 2 and 3 at its opposite ends, respectively, for the reception of cylindrical, externally threaded connecting nipples. In constructing an anode in accordance with the present invention, it is convenient, although not necessary, to use such an electrode as that shown in Fig. 3. As a preliminary step this electrode may be and often is divided at a transverse plane such as A—B (Fig. 3) spaced from one end a distance (for instance equaling one-sixth of the length of the electrode) such that it does not intersect the adjacent axial bore. There is thus provided a relatively short section 4 (Fig. 3) having the axial, internally screw-threaded bore 3. This section is designed to form a cap for the anode as hereinafter described. Preparatory to such use, the cap section is drilled to provide an axial passage, of a diameter substantially equal to the diameter of the lead-in cable which is to be employed, this passage extending from the bottom of the bore 3 to the end of the cap.

A standard connecting nipple 6 (Fig. 4) which is externally screw threaded from end to end and which is designed to engage the threaded bore of the electrode, is modified in accordance with the present invention by providing it with an axial bore 7 (Fig. 4) extending down from its upper end 8 and of a diameter such as to receive, with a convenient sliding fit, the insulating sheath 9 of the lead-in cable 10. This cable, as illustrated, is of the type having a multiple strand conductor, preferably of tinned copper wires. Where a maintenance-free, long life deep sea anode is required a good copper multi-strand well insulated welding cable or its equivalent has given excellent maintenance-free service. Also for certain semi-rigid applications of this type anode, a suitably insulated solid bus bar has been found desirable instead of a flexible "lead-in" cable.

The bore 7 in the nipple is substantially enlarged in diameter at a point spaced from the end 8 (for example, beginning at a point which is one-third, more or less, of the length of the nipple from the end 8) thus providing a cylindrical packing chamber 11. The axial length of this chamber may vary, but as here shown it is generally one-third to one-sixth of the length of the nipple. Below the lower end of the chamber 11, the bore is caused to flare downwardly with a conical taper providing an anchorage chamber 12 which terminates at the lower end 13 of the nipple. As illustrated in Fig. 4, the peripheral wall of this chamber 12 is provided with a series of axially spaced transverse grooves 14, three such grooves being illustrated, and which are here shown as substantially semi-circular in cross section. These grooves are of substantial width, for instance as herein illustrated, of the order of approximately one-twentieth the axial length of the nipple. These grooves may readily be cut with an internal lathe tool, and although here shown as of semi-circular transverse section, may be of any other section which might be preferred.

It is preferred to make the anchorage chamber 12 of tapering form since this admits of the introduction of a substantial mass of anchoring metal without unduly weakening the nipple at

its mid-portion. However, as hereinafter pointed out, the anchorage chamber may be of other shape without departing from the scope of the invention.

For illustration, in assembling the parts, one procedure is to screw the upper end of the nipple into the axial bore 3 in the cap 4, thus aligning the axial passage in the cap with the bore 7 in the nipple. The insulating sheath 9 of the cable is removed from the end portion of the cable so as to bare the conductor strands 10, as shown in Fig. 5, and the end of the cable is then drawn in through the axial passage in the cap and the bore 7 in which the insulating sheath 9 should fit with a minimum of side play. Preferably the sheath 9 extends into the packing chamber 11 for a distance, for example, of the order of one-half the length of the packing chamber. The cable is so disposed that the ends of the conductor strands 10, which usually have been "solder-tinned," are within the tapering anchorage chamber 12. Packing material 15 of asbestos fiber, wicking, or any of the usual temperature resistant compressible packing materials capable of forming a leak-tight joint, is now forced into the chamber 11 around the end of the insulating sheath 9 and around the bare conductor strands where they emerge from the sheath, the packing being driven in very tightly so as to insure a leak-tight joint between the cable and the wall of the chamber 11.

The ends of the metallic conductor strands 10 are now preferably separated and spread apart and the nipple is arranged in the inverted position shown in Fig. 5, and molten metal is poured into the anchorage chamber 12. This metal may, for example, be lead, a lead alloy, preferably capable of forming a solder or alloy union (herein referred to as a molecular union) with the exposed conductor strands. The molten metal is poured in so as to fill the chamber 12, and care should be taken to prevent the formation of deep pipes in the body of metal when thus introduced.

In solidifying, the body of metal contracts both radially and axially. By reason of its axial contraction it grips the material of the nipple intervening between adjacent transverse grooves, the internal cooling strains in the metal thus maintaining a substantially perfect electrical contact between the metal and the substance of the nipple. Moreover, the contact surfaces are of substantial extent, thus providing a very good path for the electrical current, even though of heavy amperage, and insuring low resistance at the point of union. Likewise an extremely good electrical union is formed between the anchorage metal and the conductor strands, since not only are the latter molecularly united to the metal but they are embedded in the metal and mechanically held by the latter as it contracts.

If the nipple has been made from a dense non-porous material it may be used without further treatment. However, if the nipple has been made from the usual porous graphite material, it should then be impregnated by one of the standard methods with a suitable oil, wax, or resin-impregnating compound, thereby waterproofing this assembly.

This nipple assembly is now screwed into the bore 2 in the upper end of electrode 1 and will give maintenance-free, highly efficient operation over long periods of time.

In Fig. 6 there is illustrated a modified form 75 of nipple, indicated at 16, which in general is of

the same type as the nipple 6 above described, having the axial bore 17 leading to the packing chamber 21, which in turn opens into the anchorage chamber 22. However, in this instance the anchorage chamber is cylindrical, being of uniform diameter from top to bottom. The peripheral wall of this chamber is furnished with a series of transverse grooves or channels 14 similar to the grooves above described and having the same function. The operation of assembling the cable with this nipple is substantially identical with that above described.

A further modification is illustrated in Fig. 7, wherein the cylindrical externally threaded nipple 26 is similar to that above described, having the axial bore 27 for the reception of the cable; the packing chamber 31; and the anchorage chamber 32. This chamber 32 is cylindrical like that of the nipple of Fig. 6, but instead of a series of independent grooves 14, the peripheral wall of the chamber 32 is provided with a helical groove 34, illustrated as a square screw thread. This groove may be continuous, as shown, or interrupted if preferred. It will be seen that by the provision of helical groove 34, whether continuous or interrupted, the nipple is transversely recessed interiorly at intervals along its length. This groove receives the molten metal and functions in the same way as the grooves 14 to insure a substantially perfect electrical contact between the body of anchoring metal and the substance of the nipple.

In Fig. 8 a further modification is illustrated wherein the nipple 66, similar to the nipple 6 above described, has the axial bore 67, the packing chamber 71, and the anchorage chamber 72. In this instance the anchorage chamber is provided with the series of spaced transverse recesses 74 in its peripheral wall, said recesses being arranged in any desired manner, but being individually of small circumferential extent. These recesses receive the molten metal and the latter in cooling grips the walls of these recesses very forcibly, thus providing excellent electrical union between the metal and the material of the nipple.

In Fig. 9 a further modification is illustrated. In this instance the nipple 46 may be of the pancake or disk type, being quite short axially as compared with its diameter. This nipple 46 has the axial bore 47 for the reception of the cable; the packing chamber 51; and the anchorage chamber 52. This anchorage chamber is of large diameter as compared with its axial height, and in practice its axial height need only be sufficient to insure adequate contact between the metallic anchorage block and the cable conductors. However, its diameter should be sufficient to insure an adequate gripping action between the metal anchorage block and the material of the nipple. To insure this gripping action, the upper part of the chamber 52 is formed with an annular groove 54 which extends transversely of the axis of the chamber and which is undercut so that when the metal is poured into the chamber 52 it will flow into the groove 54 and thus by the radial shrinkage of the metal in cooling will forcibly grip the annulus M between the groove 54 and the chamber 51 so as to insure good electrical contact. If the diameter of the chamber 52 be large enough, as compared with the diameter of the packing chamber 51, it may be possible, if desired, to provide more than one of the grooves 54 at the upper end of the chamber 52 for the reception of the anchorage metal.

It is thus seen that longitudinal, radial or any

other angular shrinkage of a metal terminal block is made to effect a highly efficient pressure contact between a terminal block and the electrode material which it grips. This same construction effects excellent metal-to-metal contact, usually by a soldering or alloying action of the lead-in connection (either bus bar or cable) to the terminal block.

In Fig. 10 a further modification is illustrated 10 wherein the nipple 86 is of the customary double tapered type designed for use with standard electrodes of the form in which the axial bores, corresponding to the bores 2 and 3 of Fig. 3, are tapered from the outer end of the electrode inwardly. This nipple 86 has the axial bore 87, the packing chamber 91, and the anchorage chamber 92, here shown as slightly tapered and as provided with grooves similar to the grooves 14 of Fig. 6.

In Fig. 11 there is illustrated a composite anode 20 comprising five electrodes all secured to a current distributing cap 104. Usually this cap 104 will be a circular disk, and four of the electrodes 1 will be arranged symmetrically with respect to the center of the disk (only two of these electrodes being shown). These electrodes 1 may be standard electrodes and are united to the cap 104 by standard electrode nipples 106. The fifth electrode 100 is arranged at the center of the distributing cap or disk 104 and is united to the latter by a nipple 9 which may, for example, be like the nipple illustrated in Fig. 4, and above described. Preferably a short length of rubber tubing 107 is arranged to embrace the sheath 9 of the cable 25 where the latter passes through the disk 104, thus protecting the cable from any possible damage by the sharp upper edge of the hole in the cap which receives the cable.

When a group of electrodes is employed, as suggested, it may be desirable to unite the lower ends of these electrodes by some suitable brace formed of non-conducting material. For instance the lower ends of these electrodes may be secured to a disk similar to the cap 104, but of non-conducting material. This forms no essential part of the invention and is not here illustrated. The arrangement of Fig. 11 is merely by way of suggestion of possible arrangements of multiple composite electrodes, and it is to be understood that those skilled in the art may assemble a plurality of electrodes in any desired number and in any desired relative arrangement so as to receive current from the distributing cap 104 or its equivalent. Also these electrodes may be attached to the upper side of the cap 104 or to both sides as required.

The metal employed in anchoring the cap to the nipple should be of a type having a depressed or low anodic surface solubility. Lead and some of its alloys are found to develop during use a complex surface film which greatly depresses the anodic solubility of the metal in saline waters or similar electrolytes. Some of the silver alloys have similar characteristics and may be advantageously used. For use with an aluminum bus bar or conductor, the anchorage metal may be aluminum or some of the alloys of aluminum which have the characteristic of forming a similar film of low anodic solubility. The ease with which lead or some of the lead alloys may be sweat-soldered or alloyed (molecularly united) to the end of a copper bus bar or conductor, makes the use of such metals distinctly advantageous in this construction.

When using low anodic solubility anchorage

metal in the nipple 6, the lower end 13 may be exposed directly to the electrolyte. Such a construction, which results by omitting the fifth center electrode 100 illustrated in Figure 11 is economically important for the construction of certain lightweight electrodes.

It will be obvious that the contact areas between the conductor or bus bar and the anchorage metal should be designed in accordance with the intended carrying capacity of the apparatus.

The essential details of the anode construction disclosed herein has been found by many repeated tests to maintain over long periods of time an extremely low voltage drop between a graphite electrode and its coating metallic "lead-in" conductor. Such electrodes have operated in more than fifty feet of sea water at high efficiency for thousands of hours without any maintenance attention whatever. Based on many tests, there appears to be no limit to the depth in sea or brackish water at which these electrodes will operate successfully for extended time periods; they are equally adaptable for deep water or shallow water use.

While certain desirable embodiments of the invention have been illustrated and described by way of example, it is to be understood that the invention is broadly inclusive of any and all modifications falling within the scope of the appended claims.

I claim:

1. In combination in a non-metallic electrode comprising two united parts having screw-threaded bores, one of said parts having an axial passage elading to its bore, an externally screw-threaded graphite nipple whose opposite ends are received in the bores of said respective electrode parts and which firmly unites said parts, said nipple having an axial bore aligned with the aforesaid passage in the electrode part, said bore in the nipple leading into a packing chamber within the nipple, said chamber merging with an anchorage chamber also in the nipple and having recesses in its wall, said recesses extending transverse of the axial bore, an insulated conductor extending through the axial passage in the electrode part and through the axial bore in the nipple, and having its bared end disposed in the anchorage chamber, packing within the packing chamber providing a leaktight joint between the conductor and the wall of said chamber, and a body of lead in the anchorage chamber molecularly united to the bared end of the metallic conductor, said lead adhering to said graphite nipple adjacent the transverse recesses of said anchorage chamber formed therein.

2. An anode comprising a non-metallic electrically conducting distributing plate, a plurality of carbon electrodes and means uniting the electrodes to the plate, the means for uniting one at least of the electrodes to the plate comprising a non-metallic electrically conducting nipple having screw-threaded engagement at its opposite ends respectively with the plate and electrode, said nipple and plate having aligned bores, an insulated conductor extending through said aligned bores and having a bared end disposed within a chamber in the nipple, and a body of metal embedding the bared end of the conductor and which firmly grips a portion of the nipple within its substance in response to internal cooling stress.

3. An anode assembly comprising a carbon electrode formed with a cavity in its periphery, a cap member formed with a cavity in its periphery and abutting the electrode with its cavity

communicating with the electrode cavity, a carbon nipple fitting snugly within both cavities, said cap member being formed with a bore extending therethrough and communicating with its cavity, said nipple being formed with a bore which communicates with and extends away from said cap bore to form an anchorage chamber communicating with the electrode cavity, an insulated cable conductor extending through said cap bore and said nipple bore and having a bared end extending into said anchorage chamber, the internal nipple wall which defines said anchorage chamber being formed with a plurality of longitudinally spaced transverse recesses, and a body of metal of low anodic surface solubility in said anchorage chamber molecularly united to said bared cable and adherent to the internal nipple wall between adjacent transverse recesses.

4. An anode assembly comprising a carbon electrode formed with a cavity in its periphery, a cap member formed with a cavity in its periphery and abutting the electrode with its cavity communicating with that of the electrode, a graphite nipple fitting snugly within both cavities, said cap member being formed with a bore extending therethrough and communicating with its cavity, said nipple being formed with a bore which communicates with and extends away from said cap bore, an anchorage chamber formed within said nipple and communicating 30 at one end with said nipple bore and at its other end with said electrode cavity, an insulated cable conductor extending through said cap bore and said nipple bore, said cable being bared forward of said nipple bore and extending into said anchorage chamber and terminating therein, the internal nipple wall which defines said anchorage chamber being transversely recessed, and an integrally cast body of lead in said anchorage chamber united to said bared cable end and adherent to the nipple adjacent said transverse recess.

5. An anode assembly comprising a carbon electrode formed with a cavity in its periphery, a cap member formed with a cavity in its periphery and abutting the electrode with its cavity communicating with the electrode cavity, a carbon nipple fitting snugly within both cavities, said cap member being formed with a bore extending therethrough and communicating with its cavity, said nipple being formed with a bore which communicates with said cap bore and extends away from said cap bore to form an anchorage chamber communicating with the electrode cavity, an insulated conductor extending through said cap bore and said nipple bore and having a bared end extending into said anchorage chamber, the internal nipple wall which defines said anchorage chamber being transversely recessed at intervals longitudinally of the nipple, and a body of metal of low anodic surface solubility in said anchorage chamber molecularly united to said bared conductor and adherent to the internal nipple wall between longitudinally adjacent transversely recessed portions.

6. An anode assembly comprising a carbon electrode formed with a cavity in its periphery, a carbon nipple fitting snugly within said cavity, said nipple being formed with a bore for the reception of a conductor, an anchorage chamber formed in said nipple and communicating at one end with said nipple bore and at its other end with said electrode cavity, an insulated conductor extending through said nipple bore, said conductor being bared forward of said nipple bore and extending into said anchorage

chamber and terminating therein, the internal nipple wall which defines said anchorage chamber being transversely recessed, and an integrally cast body of metal of low anodic surface solubility in said anchorage chamber united to said bared conductor end, and adherent to the nipple adjacent said transverse recess.

7. An anode assembly comprising a carbon electrode formed with a cavity in its periphery, a carbon nipple fitting snugly within said cavity, said nipple being formed with a bore adapted to receive a conductor, an anchorage chamber formed in said nipple and communicating at one end with said nipple bore and at its other end with said electrode cavity, an insulated conductor extending through said nipple bore, said conductor being bared forward of said nipple bore and extending into said anchorage chamber and terminating therein, the internal nipple wall which defines said anchorage chamber being transversely recessed at intervals longitudinally of the nipple, and an integrally cast body of metal having a coefficient of thermal expansion appreciably greater than that of carbon in said anchorage chamber united to said bared conductor and adherent to the internal nipple wall between longitudinally adjacent transversely recessed portions.

8. In combination, a carbon externally threaded nipple formed with a longitudinal bore which extends inward from one end, an anchorage chamber formed in said connecting member and communicating with said bore, an insulated conductor extending through said bore, said conductor being bared inward of said bore and extending into said anchorage chamber and terminating therein, the internal wall of said connecting member which defines said anchorage chamber being transversely recessed at intervals longitudinally of the anchorage chamber, and an integrally cast body of metal of low anodic surface solubility in said anchorage chamber molecularly united to said bared conductor, and adherent to the internal wall of said connecting member between longitudinally adjacent transversely recessed portions, said metal having a coefficient of thermal expansion appreciably greater than that of carbon.

9. In combination, a carbon externally threaded nipple formed with a cavity which defines an anchorage chamber, a conductor extending into said chamber and having a bared portion situated therein, the internal wall of said connect-

ing member which defines said anchorage chamber being transversely recessed at intervals longitudinally of the anchorage chamber, and a body of lead in said anchorage chamber united to said bared conductor, and adherent to the internal wall of said connecting member between adjacent transverse recesses.

10. In combination, an electrically conductive connecting member formed with a cavity which defines an anchorage chamber, a conductor extending into said chamber and having a bared portion situated therein, a portion of said chamber being defined by an annular groove extending around said conductor transversely thereof, 15 a solid portion of said connecting member adjacent said groove extending around said conductor and extending transversely outward of said conductor to form a shoulder partially interposed between said groove and another portion of said cavity, said shoulder being constructed and arranged such that a restricted passage interconnecting said groove and said other portion of the cavity is formed, and an integrally cast body of metal in said cavity adherent to said bared portion of the conductor and to said shoulder and that portion of the connecting member encompassed by said groove.
